UNITED STATES PATENT OFFICE

JOSEPH M. GOTTESMAN, OF PARIS, FRANCE, ASSIGNOR TO WILLIAM WILLHEIM CO., INC., OF NEW YORK, N. Y.

DESIGN FOR A TEXTILE FABRIC OR SIMILAR ARTICLE

Application filed December 1, 1932. Serial No. 46,210. Term of patent 3½ years.

To all whom it may concern:

Be it known that I, JOSEPH M. GOTTESMAN, a citizen of the United States of America, residing at 34 Avenue de l'Opera, in the city of Paris, France, have invented a new, original, and ornamental Design for a Textile Fabric or Similar Article, of which the following is a specification, reference being had to the accompanying drawing, forming a part thereof.

The figure is a plan view of a textile fabric showing the complete width of my new design, except for the portions between the

break lines which are similar to those on either side thereof. The dot and dash lines on the drawing outline substantially the design unit, which unit is repeated in regular succession as indicated by the extensions beyond the unit boundaries.

I claim:

The ornamental design for a textile fabric or similar article as shown and described.

In testimony whereof I have signed this specification.

JOSEPH M. GOTTESMAN.
